UNITED STATES PATENT OFFICE.

JOHN J. HENRY, OF WATSON, ILLINOIS.

MAGAZINE-FIREARM.

No. 873,547.

Specification of Letters Patent.

Patented Dec. 10, 1907.

Application filed June 15, 1907. Serial No. 379,256.

To all whom it may concern:

Be it known that I, JOHN J. HENRY, a citizen of the United States, residing at Watson, in the county of Effingham and State of Illinois, have invented a new and useful Magazine-Firearm, of which the following is a specification.

This invention relates to magazine firearms, and has for its principal object to 10 provide a novel form of magazine shot gun.

With this and other objects in view, as will more fully hereinafter appear, the invention consists in certain novel features of construction and arrangement of parts, herein- 15 after fully described, illustrated in the accompanying drawings, and particularly pointed out in the appended claims, it being understood that various changes in the form, proportions, size and minor details of the 20 structure may be made without departing from the spirit, or sacrificing any of the advantages of the invention.

In the accompanying drawings:—Figure 1 is a sectional elevation of the principal 25 parts of a magazine gun constructed in accordance with the invention, showing the parts closed and the hammer cocked ready for firing. Fig. 2 is a similar view showing the position assumed by the parts when the 30 forearm and barrel are moved outward and the carrier is lowered to receive a shell from the magazine. Fig. 3 is a sectional plan view of a portion of the mechanism on the line 3—3 of Fig. 2. Fig. 4 is a transverse sec- 35 tional view on an enlarged scale on the line 4—4 of Fig. 5. Fig. 5 is a sectional plan view on the line 5—5 of Fig. 4. Fig. 6 is a detail view of the releasing rod which controls the locking and unlocking of the barrel 40 and the standing breech. Fig. 7 is a trans- 45 verse sectional view on an enlarged scale, the barrel being open or forward, and the carrier being elevated. Fig. 8 is a detail perspective view of the carrier detached.

Fig. 9 is a sectional plan view on the line 9—9 of Fig. 1, illustrating the escapement mechanism for controlling the discharge 50 of cartridges from the magazine, the view being on an enlarged scale. Fig. 10 is a similar view with the parts in different positions. Fig. 11 is a detail perspective view of the main operating bar that is secured to and moves with the barrel. Fig. 12 is a perspective view of the hammer on an enlarged scale. 55 Fig. 13 is a detail sectional view through a

portion of the frame and the main operating bar, and showing the pivoted end of the carrier in elevation. Fig. 14 is a side elevation of the firearm complete, parts being broken away. Fig. 15 is a side elevation of a portion of the barrel and the front end of the magazine. Fig. 16 is an end elevation looking at the nozzle of the barrel from the front end of the magazine. Fig. 17 is a detail transverse section through the receiver. 60 Fig. 18 is a similar view showing the magazine in section and the breech end of the barrel in elevation. Fig. 19 is a side elevation of the receiver proper.

Similar numerals of reference are employed 70 to indicate corresponding parts throughout the several figures of the drawings.

The frame 10 of the gun is provided with forwardly extending side plates 11 and 12, and a top plate 13, the side plate 12 being 75 preferably made removable, so that the various parts of the lock and magazine mechanism may be examined and repaired, while the plates 11 and 13 are permanently secured together in order to secure the necessary stiffness and rigidity. To the lower portion of the forward ends of the plates 11 and 12 is connected a block or collar 14 which may be permanently secured to the plates, but preferably is made detachable for 80 the purpose of taking down the gun. For the present, however, this collar or block 14 may be considered a part of the permanent structure, and said collar serves as a support for the magazine 15, which, also, forms a sta- 85 tionary part of the gun.

Above the magazine 15 is the barrel 16, the barrel being of any desired length, and being slidably endwise toward and from the standing breech 17. The forward end of the 95 barrel is provided with a dove-tailed rib 18 that fits in a correspondingly shaped groove on top of the magazine, in order to permit free longitudinal movement and prevent lateral play, while the rear end of the barrel is 100 guided in the receiver formed by the several plates 11, 12 and 13.

Mounted on the magazine is a forearm or grip 20 which controls the locking mechanism, and by which the device is operated, a 105 single forward movement of the forearm serving to move the barrel forward from the standing breech to extract and eject the empty shell and lower the carrier into position to receive a fresh shell from the maga- 110

zine. Reverse or rearward movement of the forearm serves to elevate the carriage to hold the fresh shell in alignment with the bore of the barrel; to move the barrel back to receive the shell; cock the hammer and lock the barrel to the standing breech, placing the gun in readiness to fire.

To one side of the rear end of the barrel is secured a plate 23 that is provided at its upper and lower edges with ribs 24 that fit within grooves formed in the plates 12 and 13, and which serve as guides for the barrel. The opposite side of the barrel is flattened, as shown in Fig. 7, and fits against the flat inner surface of the plate 11, while said plate 11 is provided with a longitudinally disposed groove 25 receiving a rib 26 projecting from the barrel, these parts, also, serving as barrel guides and supports. Projecting rearward from the barrel is a bar 27 that is located near the bottom and to the left of the axis of the bore, this bar having a flattened face that bears against the flat surface of the plate 11, and the upper surface of the bar is guided by a horizontally disposed shoulder 28 projecting from the plate 11, thus forming additional supports and guides for the barrel. This bar 27 is provided with a vertical groove 30 that is arranged to receive a locking bolt 31 that is carried by the standing breech, and when the bolt is engaged in this groove the barrel is firmly locked in place in readiness for firing.

The rear portion of the standing breech 17 is provided with parallel under-cut grooves 32 and 33 for the reception of a pair of arms 34 that are formed integral with the locking bolt 31, said bolt being of considerable width, as shown in Fig. 4, and the forward face of the bolt is inclined, as shown in Fig. 5, and is provided with a small anti-friction roller 36, so that as the bar 27 is pulled rearward during the loading movement, the bolt will be pushed to the right until the groove 30 has arrived at a position to receive said bolt. The bolt is pushed to locking position by a pair of springs 37 that bear against the right hand ends of the arms 34, these springs being guided by suitable pins that project from the arms and from stationary portions of the frame. In order to permit convenient access to these parts, the arms 34 are held in position by two detachable plates 38 and 39 that form portions of the walls of the grooves 32 and 33. These plates are held in position by screws, as shown in Fig. 4, and the screws may be readily removed for the purpose of detaching the plates and permitting the removal of the locking bolt.

The movement of the bolt to release position is accomplished by a release rod 40, Fig. 6, this rod having a cam-shaped inner end 41 and being permanently secured to the forearm. When the forearm is pulled forward, the cam 41 rides against the roller 36 and

pulls the bolt to the right against the stress of the springs 37, so that the bolt will be moved clear of the groove 30, and on further forward movement the barrel can be carried outward by the forearm for the purpose of ejecting the empty shell, it being understood that the forearm has a slight unlocking movement in advance of any movement of the barrel, in order to permit this operation.

Projecting from the bottom of the barrel are two lugs 43 which enter grooves 44 in the forearm, the grooves being of greater length than the lugs, so that during the forward movement of the forearm, the latter will travel to an extent sufficient to accomplish the unlocking operation before the rear walls of the grooves engage with the lugs to carry the barrel forward. In similar manner the rearward movement of the forearm to complete the reloading and cocking would result in a preliminary movement of the forearm in advance of the barrel, but this is prevented in order that the barrel may arrive first at the closed position and before the movement of the forearm is completed.

Pivoted to the bar 27 is a lever 46 having an upwardly curved rear end which is acted upon by a leaf spring 47 tending normally to depress the rear end of the lever and elevate the forward end thereof. The forward end of the lever is arranged to move across a small groove 48 that is formed in the bar 27 at a point below the locking groove 30, (Fig. 2), and when in this position the end of the lever 46 will form a stop for the rear end of the releasing rod 40 and near the rearward or closing movement of the same the starting of the movement of the forearm on its rearward movement will engage the rear end of the rod 40 against the forward end of the lever 46, so that rod 40 will not be allowed to fully enter the groove 48. After the rod comes into contact with the lever further movement from the forearm is transmitted through this connection to the bar 27, and the barrel and its parts are carried rearward to the locking position until the groove 30 has arrived in position to receive the locking bolt.

It will be observed that that portion of the bar 27 to the rear of the groove 30 is slightly inclined, so that it may engage with the inclined forward edge of the locking bolt, and with a portion of the roller 36 so that the bolt will be forced to the right against the stress of the springs 37, and the end of the release rod 40 will, therefore, be allowed to freely pass under the locking bolt. When the parts have arrived at this last mentioned position, the curved rear portion of the lever 46 engages against a pin or roller 50 that is supported by the plate 11, and the rear edge of the lever is thrown upward and its forward end downward, so as to clear the slot 48, and thus allow the release rod and the forearm to complete their rearward move-

ment, this being accomplished by the time the rear end of the release rod has fully entered the slot 48.

The bar 27 is provided with a rearwardly extending arm 27' which operates as herein-after described, for the purpose of actuating the carrier, and this bar also serves as a means for controlling the release of the shells from the magazine and their passage onto the carrier.

At the left hand side of the rear end of the magazine and extending partly within the side plate 11 is a recess 52 in which is arranged a vertically disposed pivot pin 53 carrying an escapement lever 54 having two pallets 55 and 56, the lever being normally held in the position shown in Fig. 10 by means of a leaf spring 57, so that the pallet 55 is in position to engage against the rear-most shell in the magazine and prevent its escape under the influence of the discharging spring which may be of the ordinary helical type, (not shown). Projecting upward from this escapement lever are two pins 58 and 59, which are arranged to be engaged by a cam 60 that projects from the forward end of the bar 27. When this bar is in the rearward position, that is to say, with the parts in readiness for firing, it will be wholly free from the pins 58 and 59, and the spring 57 will hold the pallet 55 in position to prevent the accidental discharge of a shell from the magazine, while the pallet 56 will be held clear of the bore of the magazine, so that there will be no obstruction to recharging the magazine, and shell after shell may be pushed in past the pallet 55, it being observed on reference to Fig. 1 that when the gun is ready for firing, the rear end of the magazine is exposed, and fresh shells may be introduced thereto at any time.

When the parts are moved forward for reloading, the cam 60 carried by bar 27 rides against a stationary cam 61 in the recess 52 and then strikes against the arm or pin 59 of the escapement lever, rocking the latter, so that the pallet 55 is moved away clear of the bore of the magazine, as shown in Fig. 11, to permit the discharge of a shell, and at the same time the pallet 56 is moved within the bore for the purpose of engaging the next succeeding shell, thus preventing the passage of more than one shell to the carrier. During the subsequent rearward movement of the bar 27 the cam 60 will ride against the arm or pin 58 for the purpose of insuring the outward movement of the latter, and the positioning of the pallet 55, so that this movement will not be wholly dependent upon the spring 57, but is made positive, the pallet being again adjusted to position to hold the shell at the rear end of the magazine.

The carrier 64 is clearly shown in Fig. 8. This carrier has an arm 65 that projects

through a recess in the standing breech and is pivoted between lugs 67 on the trigger plate. The left hand edge of the arm is provided with a recess 68 which receives a stationary guiding lug 69 projecting upward from the trigger plate, this lug serving, also as a side guide for the arm 27', and the lug operates further as a stop for limiting the outward movement of said arm 27' and the barrel. Projecting from the left hand side of the arm 65 is a flange 70 and extending upward therefrom is an inclined lug 71. The right hand side of the arm 27' has an elongated flange 72, the rear end of which forms a cam 73 and projecting from this arm is a second cam lug 74, these cams controlling and serving as the actuating means for raising and lowering the carrier.

During the forward movement of the arm 27' the cam lug 74 engages against the arm 71 and forces the carrier downward from the position shown in Fig. 1 to the position shown in Fig. 2. During the rearward movement of the arm 27', the cam shaped end 73 of the flange 72 rides under the flange 70 of arm 65 and elevates the carrier, these two movements of the carrier being so timed as to occur while the barrel is traversing a very short distance.

The upper portion of the carrier is trough shaped in cross section, having two vertical side walls 76 and 77, and in the top of the carrier are two cartridge lifters 78 and 79. The lifter 79 comprises a lever 80 pivoted on a pin 81 and having at its rear end a curved arm 82 that is arranged to extend under the forward portion of the shell, the arm being dished or curved to partly correspond to the contour of the shell. Projecting laterally from the forward end of the lever 80 is a cam arm 83 that is arranged to be engaged by a cam lug 84 projecting downward from the bottom of the rear portion of the barrel. Under normal conditions the weight of the rear end of the lever and the arm 82 is such that the arm is held down in the trough of the carrier, but when the barrel starts on its rearward movement, the cam 84 engages a cam arm 83 and the arm 82 of the lifter is elevated, thereby raising the forward end of the shell in such position that it may enter the breech end of the barrel. The lifter 78 is merely in the form of a pair of spring elevated arms having slightly inclined faces which engage the rim of the shell, these arms being connected by a suitable cross bar 85.

The side plate 77 of the carrier is rounded, forming a high flange to prevent accidental displacement of the shells or cartridges during loading.

In order to prevent accidental movement of the shell while being elevated and moved to firing position, the upper end of the magazine and the rear end of the side plate 23 are provided with projecting tongues 91 which

will engage the shell in case it tends to roll from the carrier. Extending through the standing breech is a firing pin 93, the upper portion of which is grooved for the reception 5 of a stop lug 94 that limits movement of the pin in both directions, this lug being secured to the rear face of the standing breech by a screw or other detachable connection in order to permit the removal of the pin when 10 necessary.

The firing pin is engaged by a hammer 96 that is pivoted between lugs 97 on the trigger plate, and projecting rearward from the hammer is an arm 98 carrying anti-friction 15 rollers 99 against which bears a mainspring 100. The hammer further carries a sear engaging dog 101 which is caught by a sear 102, the latter being carried by the trigger 20 103, and being held in operative position by a suitable sear or trigger spring 104.

Projecting from the left hand side of the hammer is an arm 106 which is disposed in the path of movement of a cocking lever 107 that is pivoted to the upper rear portion of 25 the bar 27, and is held in operative position by a spring 108. The cocking lever fits within a recess in the bar, and has a rule joint connection therewith, so that during the rearward movement of the bar it will engage 30 with the arm 106 for the purpose of moving the hammer back to cocked position. On the reverse or forward movement, the spring 108 will yield, allowing the cocking lever to click over the arm 106 leaving the 35 hammer unobstructed.

In order to prevent premature firing movement of the hammer in case the latter is not fully cocked by the lever 107, or in case of accidental pressure on the trigger before the 40 parts are locked, provision is made for preventing movement of the hammer until the locking bolt 21 moves into full engagement with the groove 30.

Projecting rearward from one of the arms 45 34 of the locking bolt is an arm 110, to the rear end of which is pivoted a bell crank lever 111 free to move downward and rearward and locked from movement upward and forward by means of a lug 112. The forward 50 end of the lever is engaged by a small leaf spring 113 which yields as the rear end of the lever is engaged by an arm 115 projecting from the right hand side of the hammer as the latter is moved to cocked position, this 55 occurring before the locking bolt moves to the locking position, and in case the hammer starts on the firing movement before the bolt reaches the locking position, the arm 115 will engage the lever 111 and the hammer will be 60 held from striking against the firing pin. The arm 115 is provided with a slot 116 arranged close to the side of the hammer, and in such position as to be opposite the lever 111 when the locking bolt moves to locking position, as will be seen on reference to Fig. 5, so

that when the bolt assumes this position and the gun is in readiness for firing, the lever 111 will form no obstruction to the firing operation.

Projecting from the rear of the standing 70 breech is a pin 120 forming a support for a small helical spring 121 that is in the path of movement of the hammer. This is a rebounding spring that serves after the firing operation to throw the hammer slightly back 75 for the purpose of clearing the firing pin and preventing the latter sticking in the primer of the shell.

Arranged near the opposite edges of the standing breech are two extractors 125 and 126 arranged to engage the rim of the cartridge and fitting in suitable grooves at the breech end of the barrel when the gun is in firing position. The extractor 125 engages the right hand side of the shell rim, and is in 80 the form of a small lever, the rear end of which projects through the standing breech and is engaged by an operating spring 127. The extractor 126 is in the form of a spring arm that is provided with a projection 128, 85 the latter being disposed in the path of movement of a cam lug 129 projecting from an 90 ejector 130.

The ejector is carried by a rod 131 that is guided in a slot 132 in the plate 11, (Fig. 7), 95 and the forward end of the rod is engaged by a lug 132 projecting from the side of the barrel when the latter has nearly completed its full forward movement.

In the operation of this portion of the 100 mechanism, it will be understood that the extractors both normally engage the rim of the shell, while the ejector lies against the rear face of the shell. During the opening movement of the barrel, the extractors retain the empty shells, and when the breech end of the barrel has cleared, the forward end of the shell the lug 132 engages the forward end of the ejector rod, pulling the latter sharply forward. This movement causes the 110 cam 129 to engage the lug 128 of extractor 126, pulling the latter sidewise to the position shown in Fig. 3, while the ejector throws the empty shell out, as indicated by dotted lines in Fig. 3. 115

The firearm is provided with a safety in the form of a bar 135 which projects through a slot at the top of the frame and is provided with a thumb plate 136. The bar carries a rearwardly projecting arm 137 which may be 120 engaged by a spring catch 138 carried by the frame, the catch being arranged to hold the safety either in operative or inoperative position. The lower end of the bar carries an arm or lug 140 arranged to move directly 125 over the trigger and prevent upward movement thereof, and is further provided with an arm 141 that projects into the path of movement of the sear engaging arm of the hammer, thus forming a double catch or safety 130

that will prevent accidental discharging movement of the hammer.

The operation in brief is as follows:—The parts being in the position shown in Fig. 1, 5 the gun will be fired by releasing the hammer which strikes against the firing pin and discharges the cartridge. The marksman then pulls forward on the forearm 20, the first result of this movement being to engage 10 the cam 41 of release rod 40 with the roller 36 of the locking bolt, moving the latter to the right and out of the groove 30. By this time the rear walls of the slots 44 of the forearm engage against the rear ends of the lugs 15 43 of the barrel, and as the forward movement is continued, the barrel moves away from the breech block. The cam 74 of arm 27' engages the arm 71 of the carrier and throws the carrier down from the position 20 shown in Fig. 1 to the position shown in Fig. 2, and at this time the lug 132 of the barrel engages the ejector arm and pulls the same forward for the purpose of throwing out the empty shell which has been retained by the 25 extractor during the forward movement of the barrel. The cam 60 then acts to move the pallet 55 to release position, and the magazine spring forces the rearmost cartridge out on to the carrier, while the pallet 56 30 prevents the passage of a second cartridge from the magazine. Immediately after the lever 46 moves from engagement with the roller 50, the spring 47 moves the forward end of said lever across the slot 48. On 35 starting the return movement of the forearm, the release rod 40 engages the forward end of lever 46, and movement is transmitted therethrough to the bar 27 and arm 27'. The first effect of the movement is to release 40 the cam 60 from the finger or pin 59, the cam 60 striking the finger 58 and restoring the pallet 55 to its initial position. At the same time or about the same time, the cam shoulder 73 at the end of the flange 72 strikes 45 against the forward end of the flange 70 of the carrier, and the latter moves upward to the position shown in Fig. 1, carrying with it the shell, and the shell is received between the two extractors. As the rearward movement 50 continues, the cam 84 at the bottom of the barrel engages the cam arm 83, thus raising the cartridge lifter arm 82, so that the forward end of the cartridge will be presented in position to enter the bore of the barrel, 55 and during the further rearward movement of the barrel the shell will be fully entered therein. As the movement continues to the rear, the cocking lever 107 will engage the arm 106 and move the hammer to cocked position, 60 while the slightly inclined face of the bar 27 will force the locking bolt to release position, permitting the passage of the cam shaped end 41 of the release rod. When the barrel has moved to the full rearward position, the springs 37 will force the locking bolt 65

into the groove 30 and the lever 111 will then be carried into alignment with the groove 116, so that the hammer will be free for the firing movement.

It is to be especially noted that the gun 70 when in readiness for firing is of no greater length than the ordinary single shot or double barrel gun, inasmuch as the barrel is continuous from the standing breech to the muzzle, and there is no interval between the 75 standing breech and the breech end of the gun.

In order to lower the hammer from cocked position without discharging the shell or cartridge, one side of the hammer is provided 80 with an inclined lug 150 which may be caught by a pin 151 that extends through an opening in the side plate 12 and is normally held in the dotted line position shown in Fig. 5 by means of a spring 152, so that the lug will 85 clear the inner end of the pin. When it is desired to lower the hammer, the pin is forced in and then the trigger is pressed, whereupon the lug 150 will strike against the pin, and the movement of the hammer will 90 be checked.

In order to permit taking down, the opposite sides of the inner walls of the receiver are provided with grooves 156 that are arranged for the reception of ribs 157 projecting from 95 the sides of the rear portion of the magazine, as shown in Figs. 17 and 18. The two members are held rigidly locked by screws 158 that pass through alining openings formed in the receiver and magazine. 100

I claim:—

1. In a magazine firearm, a magazine, a 105 slide barrel, a carrier for lifting the shells or cartridges from the magazine to a position in alignment with the barrel, a lifting lever arranged on the carrier and on which the shell or cartridge rests, and means on the barrel for elevating said lifting lever to present the end of the shell or cartridge into position to enter the bore of the barrel after 110 the carrier has reached the limit of its upward movement.

2. In a magazine firearm, a receiver, a magazine tube carried thereby, a slide barrel, a carrier operating in the receiver to 115 elevate the shells or cartridges from the magazine to the rear of the barrel, and a barrel operated means on the carrier for lifting the forward end of the shell or cartridge into a position in alignment with the bore of 120 the barrel after the carrier has reached the limit of its upward movement.

3. In a magazine firearm, a receiver, a magazine tube carried thereby, a barrel slide in the receiver, a carrier operating 125 in the receiver to lift the shells or cartridges from the magazine to the rear of the barrel, and a barrel actuated means on the carrier for lifting the forward end of the shell or cartridge into a position in alignment with 130

the bore of the barrel after the carrier has arrived at the limit of its upward movement.

4. In a magazine firearm, a receiver, a magazine tube secured thereto, a barrel 5 slidable in the receiver, a carrier for elevating the shells or cartridges from the magazine to the rear of the barrel, and a barrel operated cartridge lifter arranged on the carrier and adapted to lift the forward end of the shell 10 or cartridge into a position in alinement with the bore of the barrel after the carrier has reached the limit of its upward movement.

5. In a magazine firearm, a pair of successively operable cartridge lifting devices, 15 one of which is carried by the other, and a barrel for operating both of said lifting devices.

6. In a magazine firearm, a pair of cartridge lifting devices, one of which is carried 20 by the other, and means carried by the barrel for operating said lifting devices in successive order.

7. In a magazine firearm, a receiver, a magazine carried thereby, a barrel slidable 25 in the receiver, a carrier for elevating the shells or cartridges from the magazine to the rear of the barrel, a carrier operating means connected to the barrel, a lifter supported by the carrier and arranged to lift the forward end of the shell or cartridge into alinement with the bore of the barrel, and means 30 on the barrel for operating the lifter.

8. In a magazine firearm, a receiver, a stationary magazine tube carried thereby, a 35 barrel, a carrier for elevating the shells or cartridges from the magazine to the rear of the barrel, a pivotally mounted lifting lever arranged on the carrier and having a cam shaped forward end, a carrier operating 40 means connected to the barrel, and a cam arranged on the barrel and adapted to engage the cam lever to lift the front end of the shell or cartridge into alinement with the bore of the barrel after the upward movement of the carrier is completed.

9. In a magazine firearm, a receiver, a magazine tube, a barrel slidable in the receiver, a pivotally mounted carrier operating in the receiver and having a rearwardly extending arm, said arm having a lateral flange 50 and being provided with a cam finger, and a cam arm extending rearward from the barrel and coöperating with the flange and finger to positively raise and lower the carrier.

55 10. In a magazine firearm, a receiver, a magazine tube carried thereby, a slidable barrel, an arm extending rearward from the barrel and provided with a pair of spaced cams, a pivotally mounted carrier having an arm provided with a cam flange, and a cam finger, these coöperating with said pair of cams in the raising and lowering of the carrier.

11. In a magazine firearm, a receiver, a 65 magazine tube carried thereby, an escape-

ment device controlling the discharge of the shells or cartridges from the magazine tube, a slidable barrel, a pivotally mounted carrier, and an operating arm connected to the barrel and movable therewith, said arm 70 serving to operate both the carrier and the escapement.

12. In a magazine firearm, a receiver, a magazine tube supported thereby, an escapement device controlling the discharge of the shells or cartridges from the tube, a barrel slidable in the receiver, an arm extending rearward from the barrel, an escapement operating cam on said arm, a pivotally mounted carrier having a rearwardly extending 75 arm, both arms having interfitting flanges, and interengaging cams carried by the arms and through which movement is imparted from the barrel to the carrier.

13. In a magazine firearm, a relatively 80 fixed standing breech, frame, receiver and magazine tube, a barrel slidable in the receiver toward and from the standing breech, a hammer mounted in the frame and having a laterally extending lug, and a pivotally 85 mounted locking lever supported by the barrel and arranged to engage said lug and move the hammer to cocked position, said lever being free to swing in the opposite direction to clear the lug. 95

14. In a magazine firearm, a relatively fixed standing breech, frame, receiver and magazine, a barrel slidable in the receiver toward and from the standing breech, an arm projecting rearward from the barrel, a cocking lever pivoted to the arm, said lever being held from movement in one direction and free to swing in the opposite direction, a hammer pivoted in the frame, and a lug 100 extending laterally from the hammer and disposed in the path of movement of the cocking lever. 105

15. In a magazine firearm, a relatively fixed standing breech, frame, receiver and magazine tube, an escapement mechanism 110 controlling the discharge of the shells or cartridges from the magazine tube, a barrel slidable in the receiver toward and from the standing breech, a carrier operating in the receiver to elevate the shells or cartridges 115 from the magazine to the rear of the barrel, a hammer mounted in the frame, and means operated from the barrel for controlling the movement of the escapement mechanism, the operation of the carrier and the cocking 120 of the hammer.

16. In a magazine firearm, a relatively stationary standing breech, frame, receiver and magazine tube, an escapement for controlling the discharge of the shells or cartridges from the magazine tube, a carrier operating in the receiver to elevate the shells or cartridges from the magazine to the rear of the barrel, a hammer pivoted in the frame, a barrel slidable in the receiver toward and 125 130

from the standing breech, and an operating arm secured to the barrel, said arm being provided with means for actuating the escapement, operating the carrier and cocking the hammer.

17. In a magazine firearm, a magazine tube, an escapement device at the discharge end of the magazine tube, and having a pair of pallets for successive engagement with the 10 cartridges, and a slidable barrel having means for controlling said escapement device.

18. In a magazine firearm, a magazine, an escapement mechanism comprising a pair of 15 pallets arranged to successively engage the cartridges at the discharge opening of the magazine, a slidable barrel, and means connecting the barrel to the escapement device.

19. In a magazine firearm, a magazine 20 tube open at its rear end and provided with a recess adjacent its rear end, an escapement lever pivoted in the recess and provided with a pair of detents arranged to alternately move across the bore of the magazine, a 25 spring tending to constantly maintain the outer detent in operative position, a slidable barrel, and means carried thereby for moving the outer detent to release position and the inner detent to engaging position.

20. In a magazine firearm, a magazine 30 tube open at its rear end and provided with a recess near the end, a pivotally mounted escapement lever arranged in the recess and provided with inner and outer detents, a 35 spring engaging the lever and normally holding the detent in operative position, a cam block arranged to the rear of the lever, a slid- 40 able barrel, and a cam carried by said barrel and arranged to engage the cam block and its 45 detent lever to move the outer detent to in- operative position and the inner detent to operative position.

21. In a magazine firearm, a magazine 45 tube, open at its rear end and provided with a recess adjacent to such end, an escapement lever pivoted in the recess and provided with a pair of outwardly projecting fingers, inner and outer detents carried by said lever, a cam block to the rear of the lever, a spring 50 normally tending to hold the outer detent in operative position, a slidable barrel, and a cam carried by the slidable barrel and movable by the cam block alternately into engagement with the fingers of the escapement 55 mechanism.

22. In a magazine firearm, a relatively 60 fixed standing breech, frame, receiver and magazine, a barrel slidable in the receiver toward and from the standing breech, an arm 65 extending rearward from the barrel and provided with a locking groove, an automatically actuated locking bolt carried by the standing breech and arranged to enter said groove, and means for moving said bolt to retracted position.

23. In a magazine firearm, a relatively fixed standing breech, a slidable barrel, an arm extending rearward from the barrel and provided with a groove, a spring actuated locking bolt carried by the standing breech 70 and arranged to enter said groove, a slidable forearm, and a bolt retracting device carried by said arm.

24. In a magazine firearm, a relatively fixed standing breech, frame, receiver, and 75 magazine tube, a barrel slidable in the receiver toward and from the standing breech, a grooved arm projecting rearward from the barrel, a locking bolt mounted on the standing breech and arranged to enter the groove, 80 a spring tending to move the bolt to locking position, a slidable forearm, and a bolt releasing cam carried by the forearm.

25. In a magazine firearm, a relatively fixed standing breech, frame, receiver and 85 magazine tube, a barrel slidable in the receiver toward and from the standing breech, a grooved arm projecting rearward from the barrel, a spring actuated locking bolt carried by the standing breech, and arranged to enter said groove, an anti-friction roller on the bolt, a slidable forearm on the magazine tube, a rod projecting rearward from the forearm, and a roller engaging cam carried by said arm and acting to move the bolt to 90 release position when the forearm is moved forward.

26. In a magazine firearm, a relatively fixed standing breech, frame, receiver and magazine tube, the rear face of the standing 100 breech being provided with a plurality of under-cut grooves, detachable plates forming portions of the outer walls of said grooves, a locking bolt having carrying arms fitting within said grooves, springs engaging the 105 arms and tending to move the bolt to locking position, a slidable barrel, a rearwardly projecting arm secured to the barrel and having a groove arranged to receive the bolt, a slid- 110 able forearm on the magazine tube, and a cam rod extending from the forearm and serving to move the bolt to release position.

27. In a magazine firearm, a relatively fixed standing breech, frame, receiver and magazine tube, a barrel slidable in the receiver and provided with a rearwardly projecting grooved arm, the forward portion of the arm having a notch or recess, a spring actuated lever mounted on the arm and having its forward end arranged to extend across 115 said notch or recess, a forearm slidably mounted on the magazine tube and having a loose connection with the barrel, a rod extending rearward from the forearm and having an operating cam at its rear end, said cam 120 being arranged to enter the notch or recess and to abut against the forward end of the lever during the rearward or closing movement of the barrel, a locking bolt mounted on the standing breech and adapted to enter 125 130

said groove, and a stationary member on the frame arranged to be engaged by the rear end of said lever, whereby the latter is moved clear of the notch or recess to allow full rearward movement of the cam rod and forearm.

28. In a magazine firearm, a relatively fixed standing breech, frame, a receiver, and magazine, a barrel slidable in the receiver toward and from the standing breech, a locking bolt carried by the standing breech, an arm projecting rearward from the barrel and arranged to be engaged by the bolt, a hammer, an arm extending laterally from the hammer, and means on the bolt for engaging said arm and preventing firing movement of the hammer until the bolt has moved to full operative position.

29. In a magazine firearm, a relatively fixed standing breech, frame, receiver and magazine, a barrel slidable in the receiver toward and from the standing breech, an arm projecting rearward from the barrel, a locking bolt engaging said arm, a hammer, and a hammer locking lever carried by the bolt and serving to prevent firing movement of the hammer until the bolt has moved to full operative position.

30. In a magazine firearm, a relatively fixed standing breech, frame, receiver and magazine, a barrel slidable in the receiver toward and from the standing breech, an arm projecting from the barrel, a bolt carried by the standing breech and arranged to engage said arm, a hammer, a notched arm extend-

ing laterally from the hammer, and a locking lever carried by and movable with the bolt, said lever being arranged to engage and prevent firing movement of the hammer until the bolt has moved to full locking position, and the lever has arrived in alignment with the notch.

31. In a magazine firearm, a standing breech, a pair of extractors carried thereby, a slidable barrel, an ejector bar operable from the barrel, and engaging cams on the ejector bar and one of the extractors, whereby the latter is moved to inoperative position during the ejecting movement.

32. In a firearm, a hammer having a rearwardly projecting arm, a pivoted trigger, a sear carried by the trigger and arranged to engage with the arm to hold the hammer in cocked position, and a safety having means for engaging both the trigger and the arm.

33. In a firearm of the class described, a hammer having a cam block at one side and a manually operable pin projecting through an opening in the side of the frame of the gun and disposed in the path of movement of the cam block to thereby retard the movement of the hammer.

In testimony that I claim the foregoing as my own, I have hereto affixed my signature in the presence of two witnesses.

JOHN J. HENRY.
